(57) **CLAIM**

We claim the ornamental design for a flute case, as shown and described.

DESCRIPTION

FIG. 1 is a front right perspective view of a flute case; FIG. 2 is a right side elevational view thereof; FIG. 3 is a left side elevational view thereof; FIG. 4 is a top plan view thereof; FIG. 5 is a front elevational view thereof; FIG. 6 is a rear elevational view thereof; and, FIG. 7 is a right side elevational view thereof showing a shoulder strap in phantom. The broken lines in FIG. 7 are for illustrative purposes only shown and form no part of the claimed design. The broken lines shown on the surface of the case in FIGS. 1, 4, 5 and 6 are understood to represent stitching.
